UNITED STATES PATENT OFFICE.

WILL F. P. DAVIS, OF MATTAPAN, MASSACHUSETTS, ASSIGNOR OF ONE-FOURTH TO
GEORGE MCINTOSH, OF NEWARK, NEW JERSEY, AND ONE-FOURTH TO WILBUR F.
STEWART AND ONE-FOURTH TO PAUL HUNT, BOTH OF BROOKLINE, MASSACHU-
SETTS.

DESIGN FOR A SOUND-AMPLIFIER FOR PHONOGRAHPS.

44,361.

Specification for Design.

Patented July 22, 1913.

Application filed March 7, 1913. Serial No. 752,772. Term of patent 14 years.

To all whom it may concern:

Be it known that I, WILL F. P. DAVIS, a citizen of the United States, residing at Mattapan, Massachusetts, have invented a new and original and ornamental Design for a Sound-Amplifier for Phonographs, of which the following is a specification, reference being had to the accompanying drawing, forming a part thereof.

The figure is a perspective view of a sound

amplifier for phonographs showing my new design.

I claim:

The ornamental design for a sound amplifier for phonographs, as shown.

WILL F. P. DAVIS.

Witnesses:

C. P. CLOW,

G. GLENESKIE.
